Primary Examiner — Richard E Chilcot(74) *Attorney, Agent, or Firm* — Birch, Stewart, Kolasch & Birch, LLP(57) **CLAIM**

The ornamental design for a home hub robot, as shown and described.

DESCRIPTION

1. Home hub robot

1.1 : Perspective

1.2 : Front

1.3 : Back

1.4 : Left

1.5 : Right

1.6 : Top

1.7 : Bottom

1.8 : Left, showing the home hub robot with environment

1.9 : Perspective, showing the home hub robot with environment

The broken lines shown in reproduction 1.9 indicate portions of the home hub robot that form no part of the claimed design. The broken line showing of a driving robot module in reproductions 1.8 and 1.9 is provided for the purpose of illustrating environment of the home hub robot and forms no part of the claimed design.
